(57) CLAIM

We claim the ornamental design for a food product with linked star design, as shown and described.

DESCRIPTION

FIG. 1 is a top plan view of a food product with linked star design, according to the present invention;

FIG. 2 is a left side view of the food product with linked star design of FIG. 1;

FIG. 3 is a right side view of the food product with linked star design of FIG. 1;

FIG. 4 is an end view of the food product with linked star design of FIG. 1; and,

FIG. 5 is a bottom plan view of the food product with linked star design of FIG. 1.
